UNITED STATES PATENT OFFICE.

RICHARD L. BALDWIN, OF STAMFORD, CONNECTICUT.

IMPROVEMENT IN VEHICLE-SPRINGS.

Specification forming part of Letters Patent No. 177,613, dated May 23, 1876; application filed June 4, 1874.

To all whom it may concern:

Be it known that I, RICHARD L. BALDWIN, of Stamford, in the county of Fairfield, in the State of Connecticut, have invented new and useful Improvements in Springs adapted for use in Railroad-Cars or other Vehicles, of which the following is a specification:

My invention has reference to that class of steel springs which are of elliptical form, with single exterior plates or leaves; and my invention consists in constructing and arranging, within the space between the exterior elliptical plates, a pair of auxiliary elastic plates, which are bent in equal curves in reverse direction to each other, and united by a pin or rivet at their center and line of contact, in the form of an elongated X, the ends of which auxiliary plates are made to beat and press, by their elastic action, against the inner faces of the exterior plates, and to move upon them and be kept in place by guide-rollers, as hereinafter more particularly set forth.

In the accompanying drawing, making part of this my specification, Figure 1 represents a side elevation of the spring. Fig. 2 represents, in plan or face view, one of the auxiliary plates of the spring, and showing the guide and bearing-rollers.

The elliptical plates *a a* of the spring are connected at their ends by joints of the usual form of eyes and an interlocking-pin. I prefer that these plates should taper very gradually from their centers toward their ends, but this is not absolutely essential. Within the space between the exterior plates are placed the auxiliary elastic steel plates *b b*, bent in equal curves in opposite directions to each other. They are secured together at the central point of contact by a pin or rivet, *c*. At the ends of these auxiliary springs are a pair of plates or ears on either side, as shown at *d d*. These ears are made a part of or rigidly fixed upon plates *b b*, and they project on either side of the edges of the plates *a a*, for the purpose now to be set forth: *ee* are friction and guide rollers, which have their journals and bearings within the opposite pairs of ears *d d*. These rollers are flanged at their ends sufficiently to project slightly over and

embrace the edges of the elliptical plates *a a*, as shown at *e' e'*. These auxiliary spring-plates *b b* are constructed and tempered so that their ends will require to be brought toward each other with considerable force, in order to insert them in their places between the exterior elliptical plates, and when this compressing-force is removed after the auxiliary plates are in place they will, by their elastic pressure and action, spring into and be held in their proper position, and bear with a constant elastic pressure upon the inner faces of the elliptical plates, and will move freely upon them by the action of the friction-rollers, by the flanges of which the auxiliary plates are kept in their required position, as well when the spring is at rest as when in action. The friction-rollers may be dispensed with and a straight bar substituted; and the bar or cheeks of the rollers may extend over and inclose the exterior plates, but so as to slide easily thereon.

By this construction and combination of the elliptical exterior plates and the interior auxiliary plates or springs, a soft, easy, and steady action of the spring is secured, and the exterior single elliptical plates are sufficiently supported. The stiffness or rigidity of the spring will be increased by making the interior auxiliary plates shorter and of curves of less radius with relation to the exterior plates, so that the ends of the auxiliary plates will have their bearings upon the elliptic plates nearer to the center of the spring; and, on the other hand, their softness or flexibility will be increased by making the auxiliary springs of greater length and their curves of greater radius.

My invention is applicable to springs when composed of a series of parallel elliptical plates or of parallel elliptical bars, the change in each case being only a multiplication of the same or similar parts, constructed and acting upon the same principle.

Having thus described my spring and the improvements therein, and the manner of constructing the same, I claim therein as my invention and desire to secure by Letters Patent—

1. An elliptical steel spring, composed of

the exterior plates, *a a*, and the auxiliary interior plates, or springs, *b b*, constructed, arranged, and operating substantially as set forth.

2. In an elliptical spring, composed of exterior plates and interior auxiliary plates, substantially as set forth, the guide and fric-

tion-rollers at the ends of the interior auxiliary springs, constructed and operating substantially as set forth.

RICHARD L. BALDWIN.
